JAMES G. GREENE AND LOUIS F. A. BÜCHNER, OF ELIZABETH, NEW JERSEY, ASSIGNEES TO THE SINGER MANUFACTURING COMPANY, A CORPORATION OF NEW JERSEY.

THREAD-CUTTING DEVICE.

1,208,949.

Specification of Letters Patent. Patented Dec. 19, 1916.

Application filed March 16, 1912. Serial No. 684,124.

To all whom it may concern:

Be it known that we, JAMES G. GREENE and LOUIS F. A. BÜCHNER, citizens of the United States, residing at Elizabeth, in the county of Union and State of New Jersey, have invented certain new and useful Improvements in Thread-Cutting Devices, of which the following is a specification, reference being had therein to the accompanying drawings.

This invention relates to an improvement in means for cutting the upper thread in sewing machines at the completion of a stitching operation, and particularly in buttonhole stitching machines in which the cutting of the slit occurs after a stitching operation, although certain of its features are applicable to other types of machines.

The invention has for its object to provide thread-cutting mechanism in which the cutting members are normally retracted from stitching position, but are adapted to advance for a cutting operation into close proximity with the stitch-forming mechanism and the work and to thereafter hold the cut end of the thread advantageously for production of the initial stitch of a succeeding stitching operation.

In the preferred embodiment of the improvement, the cutter-carrying member is suspended for movement endwise of the cutting blades by means of a pair of links mounted upon fulcra disposed transversely of the fulcrum of a rocking frame from which the carrying member derives movements crosswise of its cutting blades in addition to its endwise movements. The carrier is normally so positioned that its cutting and nipping elements are retracted from and in front of the needle-path, but in performing a cutting action are first moved rearward of the needle-path and then advanced to enable such elements to embrace the thread leading from the needle-eye to the work in which position they are closed to sever the thread and nip the end thereof leading to the needle.

As applied to the buttonhole stitching and cutting machine forming the subject of our applications Serial No. 576,639, filed Aug. 11, 1910, and Serial No. 597,113, filed Dec. 13, 1910, the upper cutting blade and nipping jaw are mounted upon a spring-pressed lever fulcrumed upon the carrier, such lever having a shoulder adapted in the advance

of the carrier toward stitching position to ride over the operative edge of a cam-block mounted upon one of the clamping feet of the work-holder, whereby such lever is raised to admit the needle-thread between the cutting and nipping elements and then permitted to close thereon under the action of the spring. The traveling movements of the carrier between extreme positions are imparted by connections with a reciprocatory member of the slit-cutting mechanism.

In the drawings, Figure 1 is a perspective view of the entire machine, and Fig. 2 a similar view of the forward portion of the same above the work-plate with the thread-cutting mechanism in a different stage of its operation from that of the previous figure. Fig. 3 represents a detail of the slit-cutting mechanism from which the thread-cutting mechanism derives its operative movements. Figs. 4 and 5 are perspective views upon a larger scale representing the thread-cutting mechanism from the front of the machine in different positions. Fig. 6 is an elevation, partly in section, and Fig. 7 a plan of the thread-cutting mechanism. Fig. 8 is an elevation, of the opposite side from that of Fig. 6, of the carrier and the thread-cutting and nipping members sustained thereby, and Figs. 9 and 10 front end elevations of the same parts in different positions and representing the operation upon the needle-thread.

As represented in the drawings, the machine is constructed with a frame comprising the bed-plate 1 from which rises the lower base-member 2 supporting the fixed work-plate 3, the standard 4 and overhanging arm 5 constituting the upper frame member, which latter, with the standard 4, is strengthened by the rib 6 extending from the rear of the bed-plate upwardly and forwardly to the upper boss 7 affording one of the bearings for the rotary needle-bar bushings, the other of which is journaled in the lower bearing boss 8. Journaled in suitable bearings in the standard 4 is the transverse main or driving shaft carrying the loose driving pulley 9 from which it derives its operative movements through a suitable clutch device.

The main-shaft is connected by suitable means with the reciprocating needle-bar 10 carrying the needle 11 cooperating with looper mechanism mounted upon the rotary

carrier 12 beneath the work-plate and deriving its operative movements also from a connection with the main-shaft. Traveling movements are imparted by means of suitable actuating mechanism connected with the main-shaft through the connecting bar 13 to the work-holder slide-plate 14 from which rise the bearing lugs 15 sustaining the operating rock-shaft 16 and provided with the backwardly offset extensions 17 which in practice afford fulcrum supports for the spring arms 18 carrying the clamping feet 19 between which and the plates 20, affording the lower clamping jaws, the fabric 15 *f* is clamped for a button-hole stitching and cutting operation. An operative connection is provided in practice between the rock-shaft 16 and the clamp-arms 18 whereby the latter are depressed and lifted in clamping 20 and releasing the work.

As represented in the drawings, the slit-cutting mechanism comprises, in conjunction with a lower cutting member, a cutter-block 21 secured upon the outer end of an arched 25 supporting lever 22 which is fulcrumed upon a transverse rock-shaft concentric with the stud-screw 23 tapped therein and provided with a depending arm 24 having operative connections with the lower cutting 30 member whereby the latter is shifted into and out of register with the upper-cutter member preparatory to and succeeding a slit-cutting operation.

The cutter-supporting lever 22 is connected 35 by means of the pivotal pin 25 with a link 26 constituting one member of a toggle and connected by the pin 27 with another link 28 constituting the other toggle member which is fixed upon the rocking fulcrum-pin 40 29 journaled in the frame member 5. The pin 27 affords a pivotal connection between the two links 26 and 28 of the toggle and the forward end of the pitman-bar 30 whose apertured opposite end embraces the crank-pin 31 carried by a segmental plate 32 secured to the forward face of an actuating worm-wheel 33 which is mounted upon the supporting stud 34 and adapted to be thrown 45 into operative relation with the worm 35 upon the upright worm-shaft 36 which is driven from below the bed-plate 1 by suitable means. Means are provided for maintaining the worm-wheel 33 normally out of 50 mesh with the worm 35 but for placing the same in operative relation therewith at the completion of a button-hole stitching operation to receive therefrom a single rotation for actuation of the slit-cutting mechanism.

Mounted in a depending lug 37 of the 55 lower bearing boss 8 of the bracket-arm is a fulcrum-pin 38 upon which is confined by means of the collar 39 the hub 40 of a rocking frame composed of the upwardly extending arm 41, provided with the cam-slot 42, and the depending arm 43 formed at op-

posite ends with the bearing bosses 44 and 45 spaced apart longitudinally of the hub 40 with the boss 45 depending therefrom lower than the boss 44, so that their apertures are in a plane downwardly inclined 70 toward the needle-path relatively to the hub 40 which is disposed in transverse relation to the latter.

Mounted in the bearing bosses 44 and 45 are the pivotal pins 46 and 47 from which 75 depend the parallel links 48 and 49 whose apertured lower ends embrace the studs 50 and 51 projecting laterally from the cutter-carrying bar 52. As the links 48 and 49 are of substantially the same length, it will 80 be observed that they, with the rocking frame arm 43 and carrier 52, constitute a parallel motion with the latter member inclined downwardly toward the work-plate.

Fixed upon the rocking fulcrum-pin 29 85 is a forwardly and downwardly extending arm 53 carrying a roller-stud 54 entering the cam-slot 42 of the rocking frame arm 41 and normally disposed within the lower angularly arranged portion 42^x of said slot, 90 the upper portion of which is in practice curved concentrically with the fulcrum-pin 29, as indicated more particularly in Fig. 2. As the upper-cutter lever 22 begins to descend for a slit-cutting operation in the 95 straightening of the toggle 26 28 by advance of the pitman-bar 30, the swinging of the arm 53 causes its roller-stud 54 to first traverse the angular portion 42^x of the cam-slot 42, whereby the rocking frame 40, 41, 43, 100 is oscillated upon its fulcrum-pin 38 to shift the carrier 52 from a position in front of to one rearward of the needle-path preparatory to advance of the same for a thread-engaging action, after which the traverse of the concentric portion of the cam-slot by the roller-stud 54 serves to maintain the rocking frame stationary during the remainder of the slit-cutting operation.

The cutter-supporting lever 22 carries 105 near its forward end a lateral stud-pin 55 which, as the lever descends, enters an open-ended slot 56 of a lateral cam-arm 57 rigidly connected to and in angular relation with the link 49 forming one of the swinging supports of the carrier 52. As the lever 22 continues to descend, the engagement of the stud-pin 55 with the lower side of the slot 56 serves to turn the crank-arm 57 110 downwardly about the pivotal pin 47 as a fulcrum, thereby imparting through the link 49 an endwise advance movement to the carrier 52 to bring its cutting and nipping members into operative relation with the stitch-forming and work-holding devices and into engagement with the needle-thread leading from one to the other. This operation of the stud-pin 55 is performed in opposition to the action of a spring 58 having one end secured by means 115 120 125 130

of a fastening screw 59 to one edge of the link 49, and its other end attached by the screw 60 to the frame member 5, and acting through the link 49 to maintain the carrier 52 yieldingly in upper and retracted position.

The offset forward end portion of the carrier 52 has secured within a seat formed in the back of the same by means of the screw 10 61 the shank 62 of a thread-cutting blade 63 which co-operates in practice with a cutting blade 64 formed upon the adjacent edge at the forward end of the cutter-lever 65 which is fulcrumed by means of the stud-pin 66 passing through a transverse aperture in the carrier 52 and surrounded by a spring 67 interposed between the head of the screw 66 and the carrier by means of which the cutter-lever is pressed yieldingly against the 15 adjacent operative face of the carrier and in cutting relation with the cutting blade 62.

Secured upon the forward face of the carrier 52 by means of the fastening screw 68 is the shank 69 of the lower nipping blade 25 70 whose nipping face is disposed in operative relation with that of the upper nipping blade 71 whose shank 72 is secured by means of the screw 73 upon the adjacent face of the cutter-lever 65. The cutter-lever is 30 maintained normally in its lower operative position with its upper cutting and nipping elements closed with their respective co-operating elements by means of a spring 74 having a hooked extremity 75 resting upon the 35 upper edge of the cutter-lever, its opposite end resting upon the shank of a stud-screw 76 tapped into the stud 50, and its intermediate portion resting against the lower side of the stud-screw 77 carried by the cutter-lever and serving as a stop for the edge 40 of a notch 78 in the cutter-lever 65.

The forward extremity of the cutter-lever affords a shoulder in the form of a lateral stud 79 for engagement with the inclined 45 lip 80 of a cam-block 81 fulcrumed upon a pin 82 which is mounted in the bearing lugs 83 carried by one of the clamping feet 19. The pin 82 is embraced intermediate the bearing lugs 83 by a coiled spring 84 having 50 one end anchored in the bearing lug and provided at the other end with an arm 84^x resting upon the top of the cam-block 81 and serving to maintain the same yieldingly seated upon the top of the foot 19, as represented in Figs. 4 and 5. The parts are so arranged and operated that in the advance 55 of the carrier 52 for action upon the needle-thread, the stud 79 rides up the inclined upper face of the lip 80 of the cam-block 60 and the cutter-lever 65 is thereby lifted in opposition to its spring 74 to separate the cutting and nipping elements for reception of the needle-thread, as represented in Figs. 6 and 9, and at the end of its advance movement the stud 79 rides off the end of the

cam-lip 80 to enable the spring 74 to close the upper cutting and nipping elements upon the lower co-operating element, thereby cutting and nipping the thread, as represented in Fig. 10. In the subsequent retractive movement of the carrier 52, the stud 79 engages the lower face of the cam-lip 80 and lifts the cam-block in opposition to its spring 84, thereby insuring against injurious interference of the parts in the return of 70 the cutting mechanism to initial position.

In buttonhole sewing machines as usually constructed, at the completion of a stitching operation, the lead of the upper thread between the needle-eye and the work is substantially vertical, but in the machine represented in the accompanying drawings and disclosed in detail in our applications before mentioned, and also in an application filed simultaneously herewith, Serial No. 685,490, 80 the work-clamp is retracted for the slit-cutting operation by a connection of a section of the link 13 with the slit-cutting mechanism, thus bringing the lead of the thread *n* in a backwardly inclined direction substantially as represented in Fig. 9. It is evident, however, that this shifting of the work-clamp for the slit-cutting operation is not essential to the present invention, although it provides an advantageous positioning of 85 the thread for introduction between the thread-cutting and nipping elements.

In the operation of the machine as herein shown and described, the stitching operation immediately follows the closing of the work-clamp upon the fabric, the initial thread end *a'* being maintained nipped between the upper and lower nipping jaws 71 and 70, as represented in Fig. 4, in such manner that the lead of this branch of the thread is forwardly of the needle path and upon the side thereof from which the thread issues from the needle-eye, thereby insuring against the twisting of the initial thread-loop presented for the loop-taker and avoiding the skipping of the initial stitch. At the completion of the second side stitching operation, the stitch-forming mechanism is arrested and the slit-cutting mechanism operated to form the slit intermediate the spaced overseams composing the sides of the buttonhole, the work-holder being at the same time retracted to bring the stitched and still uncut buttonhole into register with the slit-cutting members. Simultaneously with the operation of the slit-cutting mechanism, the thread-cutting action takes place by means of its operative connection therewith, as before described, the carrier 52 advancing toward the stitch-forming mechanism correspondingly with the advance of the upper slit-cutting member toward the fabric and retreating simultaneously with the return of the upper slit-cutting member to initial retracted position. The term "slit-cutting mechanism" 120

used herein includes mechanism comprising cutting members or a cutting member, of any suitable size and character for cutting the fabric, either prior to or after the stitching operation.

Having thus set forth the nature of the invention, what we claim herein is:—

1. In a buttonhole stitching machine, the combination with stitch-forming mechanism, and slit-cutting mechanism, of distinct thread-severing mechanism mounted separately from and connected with and controlled in the timing of its action by said slit-cutting mechanism.
2. In a buttonhole stitching machine, the combination with stitch-forming mechanism, of slit-cutting mechanism, thread-severing mechanism independent of the latter, and means for simultaneously actuating said slit-cutting and thread-severing mechanisms.
3. In a buttonhole stitching machine, the combination with stitch-forming mechanism, of slit-cutting mechanism, thread-severing mechanism independent of the latter, and common actuating means for said slit-cutting and thread-severing mechanisms.
4. In a buttonhole stitching machine, the combination with stitch-forming mechanism, and slit-cutting mechanism, of distinct thread-severing mechanism mounted separately from and having an operative connection with said slit-cutting mechanism and deriving its operative movements through said connection.
5. In a buttonhole stitching machine, the combination with stitch-forming mechanism, of a thread-severing device including separable cutting elements, means for bodily moving said thread-severing device into and out of thread-severing position, and including a movable actuating member connected with and adapted to impart the initial movement to the severing device, and a second movable actuating member initially disconnected from the severing device but adapted to assume operative relation with the latter after the action of the initially connected member and impart a subsequent bodily movement to said severing device in a direction at an angle to the direction of the initial movement, and means for opening and closing said cutting elements.
6. In a buttonhole stitching machine, the combination with stitch-forming mechanism, a work-holder, and slit-cutting mechanism, of a thread-severing device including separable cutting elements, means connected with and actuated by said slit-cutting mechanism for moving said thread-severing device into and out of operative relation with the thread held by said stitch-forming mechanism, and means carried by the work-holder for controlling the opening and closing of said cutting elements to admit and sever the thread.

7. In a buttonhole stitching machine, in combination, stitch-forming mechanism including a reciprocating needle, a thread-severing and nipping device comprising a carrier and cutting and nipping elements mounted thereon, transversely movable pivoted supporting elements for said carrier, means for bodily moving both of said supporting elements to move the carrier laterally from a retracted position at one side of the needle path, and means for moving said supporting elements about their pivots to impart an endwise movement to the carrier to bring its cutting and nipping elements to the opposite side of the needle path and into operative engagement with the thread leading from the needle-eye.

8. In a buttonhole stitching machine, the combination with stitch-forming mechanism including a reciprocating needle, of a thread-severing and nipping device comprising a carrier movable in different directions in angular relation each with the other and sustaining pairs of separable cutting and nipping elements, of means for maintaining said carrier normally retracted with its cutting and nipping elements at one side of the needle-path for holding the thread-end for the initial stitch of a group, and means including separate members acting independently and alternately upon the carrier for laterally shifting and advancing said carrier to bring its cutting and nipping elements into operative position at the opposite side of the needle-path for a thread-severing and nipping action.

9. In a buttonhole stitching machine, the combination with stitch-forming mechanism including a reciprocating needle, of a thread-severing device comprising a carrier, coöoperating cutting elements sustained by said carrier at one side of the needle path and out of line with the needle, shifting means connected with said carrier for moving the cutting elements to the opposite side of the needle, means acting positively and independently of said shifting means for moving said cutting elements into operative position adjacent the needle, and means distinct from said positively acting means for closing said cutting elements to sever the thread.

10. In a buttonhole stitching machine, the combination with stitch-forming mechanism including a reciprocating needle, of a thread-severing device comprising a carrier, coöoperating cutting and nipping elements sustained by said carrier at one side of the needle path and out of line with the needle, shifting means connected with said carrier from moving the cutting elements from initial position to a position at the opposite side of the needle, means connected with said carrier and movable differentially with respect to said shifting means for moving end-

wise each of said cutting elements into operative engagement with the thread at said opposite side of the needle, means for closing said cutting elements to sever the thread 5 and means for returning said carrier to initial position.

11. In a buttonhole stitching machine, the combination with stitch-forming mechanism including a reciprocating needle, of a 10 thread-severing and nipping device comprising a rocking frame, a fulcrum therefor arranged transversely to the needle-path, a carrier sustained by said rocking frame and movable thereon in substantially the plane 15 of said fulcrum, pairs of separable cutting and nipping elements mounted upon said carrier and sustained normally at one side of and retracted from the needle-path, and actuating means including independent connections 20 with said rocking frame and said carrier whereby said frame is rocked to direct the carrier to the opposite side of the needle-path and the carrier is advanced for engagement of its cutting and nipping elements 25 with the thread leading from the needle-eye.

12. In a buttonhole stitching machine, the combination with stitch-forming mechanism including a reciprocating needle, of a 30 thread-severing and nipping device comprising a rocking frame, a fulcrum therefor arranged transversely to the needle-path, a pair of links suspended from said rocking frame by pivotal connections disposed transversely to said fulcrum, a carrier pivotally connected at different points with said links, pairs of separable cutting and nipping elements mounted upon said carrier and sustained normally at one side of and retracted 35 from the needle-path, and actuating means including independent connections with said rocking frame and said carrier whereby said frame is rocked to direct the carrier to the opposite side of the needle-path and the carrier 40 is advanced for engagement of its cutting and nipping elements with the thread leading from the needle-eye.

13. In a buttonhole stitching machine, the combination with stitch-forming mechanism 50 including a reciprocating needle, and slit-cutting mechanism, of a thread-severing and nipping device comprising a rocking frame, a fulcrum therefor arranged transversely to the needle-path, a carrier sustained by said 55 rocking frame and movable thereon in substantially the plane of said fulcrum, pairs of separable cutting and nipping elements mounted upon said carrier and sustained normally at one side of and retracted from 60 the needle-path, and actuating means including independent connections between the slit-cutting mechanism and said rocking frame and said carrier, respectively, whereby said frame is rocked to direct the carrier to the 65 opposite side of the needle-path and the car-

rier is advanced for engagement of its cutting and nipping elements with the thread leading from the needle-eye.

14. In a buttonhole stitching machine, the combination with stitch-forming mechanism 70 including a reciprocating needle, and slit-cutting mechanism, of a thread-severing and nipping device comprising a rocking frame, a fulcrum therefor arranged transversely to the needle-path, a carrier sustained by said rocking frame and movable thereon in substantially the plane of said fulcrum, pairs of separable cutting and nipping elements mounted upon said carrier and sustained normally at one side of and retracted from 75 the needle-path, a permanent connection between the slit-cutting mechanism and said rocking frame whereby the carrier is directed toward the opposite side of the needle-path, and a normally disconnected connection 80 between the slit-cutting mechanism and the carrier whereby the latter is actuated after the shifting of the rocking frame to advance its thread-cutting and nipping elements into operative relation with the 85 stitch-forming mechanism.

15. In a buttonhole stitching machine, the combination with stitch-forming mechanism including a reciprocating needle, and slit-cutting mechanism including a reciprocating 90 member, of a thread-severing and nipping device comprising a rocking frame, a fulcrum therefor arranged transversely to the needle-path, a carrier sustained by said rocking frame and movable thereon in substantially the plane of said fulcrum, a cam-arm operatively connected with said carrier, cutting and nipping elements mounted upon 95 said carrier and sustained normally at one side of and retracted from the needle-path, a permanent connection between the slit-cutting mechanism and said rocking frame for rocking the latter upon its fulcrum, and a stud-pin mounted upon said reciprocating member of the slit-cutting mechanism and adapted for engagement with said cam-arm for imparting operative movements to 100 said carrier.

16. In a buttonhole stitching machine, the combination with stitch forming mechanism, 115 of a carrier normally retracted to one side of the path of said stitch-forming mechanism, a cam-block mounted at the other side of said path, thread-cutting means sustained by said carrier and comprising a fixed member and a movable member coacting therewith, and means intermittently engaging the carrier to positively move the same across the path of said stitch-forming mechanism, whereby said movable cutting member is 120 brought into direct engagement with said cam-block and is actuated thereby to sever the thread of said stitch-forming mechanism.

17. In a buttonhole stitching machine, the 125

- combination with stitch-forming mechanism, and a work-holder, including a clamping device, of a thread-severing device including a carrier supported independently of the work-holder and sustaining the fixed member of a shear-cutter, means for sustaining said carrier for endwise movement toward and from the work-holder, a spring-pressed cutter-lever fulcrumed upon said carrier, a movable 5 shear-cutter member carried by said cutter-lever in operative relation with the fixed cutter-member, a cam-member sustained by the work-holder within the path of movement of said cutter-lever, means for imparting operative movements to said carrier to effect the engagement of the cutter-lever with said cam-member and means whereby the cam-member may be retracted out of the path of said cutter-lever as the latter returns from the work-holder.

18. In a buttonhole stitching machine, the combination with stitch-forming mechanism, and a work-clamp, of a movable carrier mounted independently of said clamp and normally retracted therefrom, thread-cutting means sustained by said carrier and comprising a fixed cutter member and a movable cutter member coacting therewith, a cam-block sustained by said work-clamp, and means for operating said carrier whereby the movable cutter member is brought into engagement with, and is actuated by, said cam-block, to sever the thread of said stitch-forming mechanism.

19. In a buttonhole stitching machine, the combination with stitch-forming mechanism, and a work-clamp, of a thread-severing device including a carrier mounted independently of said clamp and sustaining a fixed cutter member and a movable cutter member coacting therewith, a lateral stud carried by said movable cutter member, a cam-block pivot-

ally mounted upon the work-clamp and provided with a cam-lip having operative faces within and inclined to the path of movement 45 of said stud upon the movable cutter member, and means for imparting operative movements to said carrier to effect the engagement of said stud with said cam-lip of the pivotally mounted cam-block. 50

20. In a buttonhole stitching machine, the combination with stitch-forming mechanism, and a work-holder, of a thread-severing device including a carrier sustaining the fixed member of a shear-cutter, means for sustaining 55 said carrier for endwise movement toward and from the work-holder, a spring-pressed cutter-lever fulcrumed upon said carrier, and provided with a lateral stud, a movable shear-cutter member carried by 60 said cutter-lever in operative relation with the fixed cutter-member, a cam-block pivotally mounted upon the work-holder and provided with a cam-lip having operative faces within and inclined to the path of movement 65 of said stud upon the cutter-lever, and means for imparting operative movements to said carrier to effect the engagement of said stud with said cam-lip of the pivotally mounted cam-block, whereby the cutter-lever 70 may be turned upon its fulcrum during the movement of the carrier toward the work-holder and the cam-block may be turned out of the path of the carrier as the same is retracted from the work-holder. 75

In testimony whereof, we have signed our names to this specification, in the presence of two subscribing witnesses.
